CASTING MACHINE FOR LINING BEARINGS

William Henry Tobener, Jr., Cleveland, Ohio, assignee to Thompson Products, Inc., Cleveland, Ohio, a corporation of Ohio

Application January 12, 1946, Serial No. 640,916

8 Claims. (Cl. 22—123)

1

This invention relates to casting machines especially adapted for lining bearings.

Specifically, the invention deals with casting machines for babbittting bearings such as connecting rods for internal combustion engines.

While the machines of this invention are generally useful for die casting, and especially for lining hollow articles with metal, they are especially useful in connection with the rebabbittting of connecting rods for internal combustion engines, and will hereinafter be specifically described for such usage. It should be understood, however, that the invention is not limited to use of the machine for rebabbittting connecting rods.

According to this invention the machine is provided with a work support receiving a spring-pressed mandrel or core member therethrough. This mandrel projects above the work support and receives a pour plate on its top end. The pour plate and work support have work-receiving depressions around the mandrel to center the work relative to the mandrel. In addition, the pour plate and work support have bead-forming recesses surrounding the mandrel to receive metal from the pour plate for forming beads on the opposed faces of the work. The work, if in several sections, is first connected to hold the sections in their operative relation, and is then seated around the mandrel in the depression of the work support. The pour plate is next mounted on top of the work to receive the top face of the work in its work-receiving depression. A clamping device acts on the pour plate to clamp the work in position. This clamping device is effective to depress the mandrel against the action of the spring so that the work is firmly held in fixed position between the work support and pour plate, irrespective of the height or width of the work, and without interference from the mandrel. The top face of the pour plate has a molten metal-receiving trough and apertures join the bottom of this trough with the space between the mandrel and work so that molten metal will completely fill this space and also flow into the bead-forming recesses for forming beads on the top and bottom faces of the work. When the molten metal has solidified, the clamping device is released, the pour plate is rotated to break the gates which extend through the apertures, the plate is then removed from the work, a foot pedal is depressed to retract the mandrel from the work, and the lined work piece is easily lifted from the work support. The mandrel can be of any desired shape to provide the selected contour

2

for the bearing or lining produced by the casting operation.

A feature of this invention resides in the provision of radially extending keys on the mandrel to form lubricant grooves in the bearing produced by the casting operation and to facilitate separation of the pieces of a multi-section bearing.

Another feature of the invention is the provision of bead-forming recesses in the pour plate and in the work support around the mandrel for forming bearing beads on the opposed end faces of the work to build up worn or undersized end faces.

A still further feature of the invention is the provision of a spring-pressed retractable mandrel cooperating with a clamping device so that the work is firmly held in position for the casting operation without interference from the mandrel.

A still further object of the invention is to provide a spring-pressed mandrel arrangement that is readily retracted from the finished casting without damaging the casting.

A still further feature of the invention is to provide a spring-pressed mandrel and clamping assembly for accommodating work pieces of different widths.

An object of the invention is to provide a simple, relatively inexpensive casting machine that will quickly line work pieces such as connecting rods with metal such as babbitt or other bearing metal.

A further object of the invention is to provide a casting machine for rebabbittting bearings which machine is adapted to accommodate bearings of different widths without necessitating change of dies, core pieces, or the like.

A still further object of the invention is to provide a casting machine which quickly forms a molten metal-receiving cavity in or around a work piece.

40 A still further object of the invention is to provide a babbittting machine which will simultaneously form babbittted end faces and main bearing surfaces with oil grooves.

45 A further object of the invention is to provide a connecting rod rebabbittting machine which will line a split connecting rod bearing with babbitt metal.

50 A further object of this invention is to provide a rebabbittting machine that will simultaneously babbitt all sections of a multi-section bearing.

A specific object of the invention is to provide a babbittting machine that will simultaneously from bearing linings in both halves of a split connecting rod bearing or the like without interfering with the separation of the split sections.

Other and further objects of the invention will be apparent to those skilled in the art from the following detailed description of the annexed sheets of drawings which, by way of a preferred example only, illustrate one embodiment of the invention.

On the drawings:

Figure 1 is a side elevational view of a casting machine according to this invention and illustrating in dotted lines the manner in which a connecting rod is mounted of the machine for the casting operation.

Figure 2 is a front elevational view of the machine of Figure 1.

Figure 3 is an enlarged fragmentary vertical cross-sectional view, with parts in elevation, taken along the lines III—III of Figure 1, and III—III of Figure 4.

Figure 4 is a fragmentary top plan view of a connecting rod with the mandrel of the casting machine mounted therein and illustrating the babbitt bearing formed by the casting machine around the mandrel.

Figure 5 is a fragmentary inside elevational view taken along the line V—V of Figure 4 but with the mandrel removed, and illustrating the babbitt liner formed by the machine of this invention.

Figure 6 is an isometric view of a portion of the machine of this invention illustrating the manner in which the work piece is mounted on the machine.

Figure 7 is a top plan view of the pour plate for the machine of this invention.

As shown on the drawings:

The machines of this invention include a table or supporting frame 10 shown in Figures 1 to 3 and 6 having upstanding supporting legs 11 and a flat horizontal table top 12.

A work supporting die 13 is mounted on hollow posts or studs 14 supported on the table top 12. Bolts 15 are passed through the four corners of the die 13, through the hollow studs 14, and through the table top 12 to receive nuts 16 on their threaded ends which seat against the underside of the table top 12 to fixedly secure the die 13 in spaced relation above the table top. The die 13 can be readily replaced or removed by removal of the nuts 16 from the bolts 15.

As best shown in Figure 3, the work support die 13 has a vertical cylindrical aperture or bore 17 therethrough slidably receiving therein a metal core member or mandrel 18. This mandrel projects above the top face of the die 13 to extend through the work piece and provides the inner forming surface for the lining or bearing metal that is cast into the work piece. The mandrel 18, as shown in Figures 3 and 4, carries keys or inserts 19 which have pointed ends 19a projecting radially from diametrically opposite sides of the mandrel and provide ridges on the surface of the mandrel. The projecting ends 19a of the keys fit into grooves such as 17a provided in the aperture 17. As will hereinafter be more fully described, the pointed ends 19a of the keys 19 form grooves in the babbitt liner at the dividing line between the sections of a connecting rod so that these sections can be readily separated, and so that the linear will have lubricant-conveying grooves along the entire width thereof.

The top face of the die 13 has a cylindrical counterbore 20 therein surrounding the aperture 17 and providing a work-receiving depression with a bottom shoulder 21 to support the work on the die and to center the work relative to the mandrel.

A bead-forming recess 22 is formed in the top face of the die 13 beneath the shoulder 21. This recess 22 extends around the aperture 17 in full communication therewith.

5 A bolt 23 extends freely through an aperture 12a in the table top 12 under the die 13 and has a threaded upper end 23a threaded into the lower portion of the mandrel 18. This bolt also extends freely through an aperture 24a in a 10 spring-pressed plate 24 mounted under the table top 12. Studs 25 depend from the table top 12 to slidably receive the plate 24 thereon. Coil springs 26 are disposed around the studs 25 between the bottom face of the plate 24 and washers 27 seated on the heads 25a of the studs 25. The plate 24 is therefore spring urged toward the table top 12 but can be lowered relative to the table top 12 upon compression of the springs 26.

15 A nut 28 is threaded on the bolt 23 between the top face of the plate 24 and the bottom face of the table 12. The spring pressed plate 24 acts on this nut 28 to yieldably urge it against the under face of the table top 12 so that the bolt 23 will carry the mandrel to project above the top face of the die 13 and through work mounted on the die.

20 As shown in Figures 1 and 2, the bolt 23 projects beyond the spring pressed plate 24 and through the bight portion of a U-shaped member or yoke 29. Nuts 30 are threaded on the bottom end portion of the bolt to thrust against the top and bottom faces of the bight portion of the yoke 29 for affixing the yoke to the bolt.

25 A link 31 projects into the space between the side legs of the yoke 29 and is connected to the yoke by means of bolts 32. Spacers 33 on the bolts 32 are positioned between the faces of the links and inner faces of the yoke legs to hold the link in the center of the yoke.

30 The link 31 depends between the legs 11 of the table top and is pivotally connected at its lower end by means of a bolt 34 to a foot lever or pedal member 35 which is pivoted at its inner end to a cross-brace 36 carried by the rear legs 45 of the machine in spaced relation above the bottoms of the legs. A bolt or stud 37 pivotally connects the lever 35 to the brace 36. The lever 35 projects beyond the front face of the table 10 and a foot pad 35a is secured to the top of the free end of the lever. When the free end of the lever 35 is depressed the link 31 will pull the bolt 23 downwardly, the nut 28 on the bolt will engage the top face of the spring pressed plate 24, and the mandrel will be retracted through the aperture 17 of the die 13 to withdraw the mandrel from the work piece, or at least loosen it from the lining in the work piece.

35 As shown in Figures 1 to 3, a pour plate 38 is removably mounted on top of the mandrel 18. This pour plate 38 has a hollow central boss portion 38a providing an open-bottomed recess 39 receiving a boss or post 18a on the top of the mandrel. The post 18a centers the pour plate 38 on the mandrel. An annular trough 40 is provided in the top face of the pour plate 38 around the boss 38a thereof to form a molten metal-receiving chamber. A plurality of apertures 41 are formed at spaced intervals through the pour plate 38 around the boss 38a thereof.

40 The bottom face of the pour plate has a cylindrical bore 42 extending for a slight distance therein to terminate in a horizontal shoulder 43. This bore provides a work-receiving recess for the top face of the work. A bead-forming recess 44 is provided above the work-receiving recess in

the underface of the pour plate 38 and this recess is connected to the trough 40 in the top face of the plate through the apertures 41. Molten metal poured into the trough 40 flows through the apertures 41 into the recess 44 and from the recess flows around the mandrel within the work piece to the bottom recess 22 as will be more fully hereinafter described.

A handle 45 is welded to the periphery of the pour plate 38.

As shown in Figures 1, 2, and 6 a toggle clamp device 46 is mounted on the table top 12 to act on the pour plate for clamping the work piece between the pour plate and die around the mandrel.

The clamping device 46 includes a supporting plate 47 mounted on studs 48 carried by the table top 12. Opposed angle brackets 49 are bolted or riveted to the supporting plate 47 and have upstanding spaced opposed flanges 49a receiving the end of a clamping bar 50 therebetween. A pivot pin 51 extends through the flanges 49a and through the rear end of the bar 50 to pivotally connect the bar to the flanges. The free or forward end of the bar 50 has a work-engaging member 52 pivoted thereon to act on the boss 38a of the pour plate 38. A handle 53 has bifurcated opposed portions 53a—53a straddling the flanges 49a and pivoted thereto by means of pins such as 54. A pair of links 55 project between the bifurcated or strap portions 53a of the handle and are pivoted thereto by means of a pin 56. The other ends of the links straddle the clamping bar 50 and are pivoted thereto by means of a pin 57. A stop pin 58 extends transversely through the clamping bar 50 in spaced relation forwardly from the pivot pin 57.

To move the work-engaging member 52 against the boss 38a of the pour plate 38 the handle 53 is pulled forwardly until it strikes the stop pin 58 as shown in Figure 1. When the handle engages the stop pin 58, the links 55 will have slightly passed their dead center positions relative to the pivots 56 and 57, and these links will then positively hold the clamping bar against upward movement away from the pour plate as a result of pressure on the clamping bar tending to urge it in this direction.

To release the clamp, the handle 53 is pushed backwardly to the position shown in Figure 6. This movement pulls the clamping bar 50 through a greater arc than the arc through which the handle 53 is swung, and the work-engaging end 52 of the clamping bar 50 will be moved completely away from the pour plate. As the handle 53 approaches the stop 58, movement of the clamping bar takes place at a lower rate than the rate of movement of the handle because the links 55 are substantially parallel to the handle. A leverage advantage is thus obtained because the links act as a toggle.

In operation of the machine of this invention, a work piece, such as a conventional connecting rod 60 with a split main bearing portion composed of a half-bearing head 61 integral with the rod portion of the connecting rod and a strap member or bearing portion 62 bolted to the head 61 by means of conventional bolts 63, provides an open-ended central aperture 64 of larger diameter than the mandrel 18. This aperture is lined with babbitt or other bearing metal by the machines of this invention and the head 61 and yoke 62 are simultaneously babbitted or lined with bearing metal.

The connecting rod 60 has opposite end faces 65 surrounding the aperture 64 and these end faces may be worn so that it is desired to cover them with babbitt or other bearing material to produce bearing faces thereon and thus build up the worn faces. The machines of this invention provide for the building up of the end faces 65 simultaneously with the forming of a bearing lining in the aperture 64.

10 Since the yoke section 62 must be separated from the head 61 to mount the connecting rod on a crankshaft, the babbitt lining must be separated at the dividing line 66 between the head and yoke. For this purpose the keys 19 are provided on the mandrel 18 so that the babbitt metal will be very thin at the dividing line 66 and can be easily separated.

As shown in Figures 1 to 3 and 6, the connecting rod 60 is mounted on the work-supporting die 13 with the bottom face 65 thereof extending into the work-receiving recess 20 and resting on the shoulder 21 of the die. A portion of the face 65 is exposed to the bead-forming recess 22 of the die. The mandrel 18 projects completely through the aperture 64 of the connecting rod, and the connecting rod is rotated to align the keys 19 with the dividing line 66 between the head and yoke 62. The pour plate 38 is then mounted on the mandrel 18 and centered thereon by the post 18a of the mandrel. The top face 65 of the connecting rod 60 projects into the work-receiving recess 42 of the pour plate 38 and abuts the shoulder 43 at the bottom of this recess. As shown in Figure 3, however, a portion of this top face 65 is fully exposed to the bead-forming recess 44.

The recess 20 centers the connecting rod so that the aperture 64 therethrough will be equally spaced from the cylindrical outer wall of the mandrel 18.

40 The toggle clamping device 46 is then actuated to move the work-engaging member 52 on the clamping bar 50 against the top of the boss portion 38a of the pour plate. This will securely 45 clamp the connecting rod between the pour plate and the die. Since the mandrel is spring pressed, it is moved downwardly to permit this clamping relationship of the parts. The nut 28 is preferably so adjusted that the mandrel will carry 50 the pour plate 38 in spaced relation above the top face 65 of the connecting rod until the clamping bar 50 acts on the pour plate to depress it into clamping engagement with the top face of the connecting rod. This adjustment is desirable 55 since release of the clamping device from the pour plate after the casting operation will bring about separation of the pour plate from the connecting rod because the mandrel will push the pour plate above the connecting rod.

60 Molten metal such as babbitt is poured into the chamber 40 of the pour plate 38 and flows through the apertures 41 into the bead-forming recess 44 from which it flows into the space in the aperture 64 around the mandrel 18 and 65 thence into the bead-forming recess 22. All of these spaces will be filled with metal and, as soon as the metal has solidified, the clamping device is released, the pour plate rotated by the handle 65 to break the gates in the apertures 70 41, and the foot pedal is depressed to retract the mandrel 18 through the connecting rod, thereby releasing the lined rod from the machine. The machine is immediately ready for the next casting operation by slipping another connecting 75 rod over the mandrel, by melting gate metal from

the pour plate, which gate metal is easily removed since it will not coat the plate, and by again actuating the clamping device to lock the work piece between the pour plate and the stationary die.

As illustrated in Figures 4 and 5, the connecting rod members 61 and 62 have babbitt linings 61a and 62a respectively therein, which linings are separated by V-shaped grooves 67 formed by the pointed ends 19a of the keys 19. These grooves 67 may completely separate the linings 61a and 62a, or may have a very thin connecting layer of bearing material at their bottom ends. This very thin layer is readily ruptured by separation of the connecting rod halves 61 and 62. The lining material extends over the end faces 65 of the connecting rod to form beads 68 thereover. These beads are of diminished width at the grooves 67 and will also rupture or break at these points when it is desired to separate the connecting rod pieces 61 and 62. However, the lined bearing is radially bored and ground at the end faces thereof to the desired dimensions before the sections 61 and 62 are separated and unless the width of the connecting rod is materially undersize, the beads 68 are ground to a very thin section and, in most instances, are completely ground off. Therefore, no complications result in attempted separation of the connecting rod sections 61 and 62, by virtue of the beads extending across the dividing line between the sections.

From the above descriptions it will, therefore, be clear that this invention provides an easily operated and relatively inexpensive machine for simultaneously lining the sections of a multi-section bearing to not only build up the main bearing portion thereof and provide lubricant grooves therein, but to also build up the end faces of the sections in the event the same are undersize.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A casting machine for babbittting connecting rod bearings and the like which comprises a table having a flat top, a vertically apertured horizontal work-supporting die detachably mounted on said top in spaced relation therabove, a plurality of studs depending from the table top, a plate slidable on said studs, springs carried by said studs urging the plate toward the top of the table, a vertical bolt slidable through said plate and table top, a stop nut threaded on said bolt between the table top and plate to limit upward movement of the bolt and to act on the plate for compressing the springs upon downward movement of the bolt, a foot pedal pivoted on the lower portion of the table, a link connecting the pedal with the bolt for pulling the bolt downwardly when the pedal is depressed, a mandrel slidable in the aperture of said die and secured on said bolt for movement therewith, a pour plate detachably seatable on top of said mandrel, the top face of said die and the bottom face of said pour plate having opposed work-receiving depressions and bead-forming recesses, said pour plate having a molten metal-receiving trough therein together with apertures therethrough joining the bottom of the trough with the bead-forming recess and spaces between the mandrel and work, and a toggle clamp device mounted on

said table top having a clamping bar for acting on the pour plate to clamp the work between the die and pour plate and to depress the mandrel to accommodate full seating of the pour plate on the work.

5. A casting machine for simultaneously lining the bearing halves of a connecting rod or the like which comprises a work support, a core member slidably mounted in said work support and projecting therefrom through a connecting rod mounted on the support, said core having radially extending keys adapted to be aligned with the dividing line between the halves of the connecting rod to form grooves in the lining at said dividing line, means for pouring molten metal around said core into said connecting rod, and means for retracting the core from the solidified metal in the connecting rod.

10. A casting machine for simultaneously babbittting the sections of a multi-section bearing which comprises a work support for receiving the bearing thereon, a core member slidably relative to said work support for projecting through the bearing, said core member having a peripheral face for shaping the inner face of the lining to be cast in the bearing, radially projecting keys on said core member adapted to be aligned with the dividing lines between the bearing sections to form grooves in the bearing metal at said dividing lines, a member for overlying a bearing on said work support, said member having gate openings therethrough communicating with the space in the bearing around the core, means acting on said member to clamp the bearing between the member and work support, and means for retracting the core from the bearing to release the lined bearing from the machine.

15. A casting machine for lining bearings or the like which comprises a table, a work-supporting die detachably fixed in stationary relation to the top of the table in spaced relation above said top, said die having an aperture therethrough, a mandrel slidable mounted in said aperture, spring-pressed means acting on said mandrel and supported by said table for urging the mandrel upwardly through the work support, means acting in opposition to the thrust of said spring pressed means for retracting the mandrel through work on said support, a pour plate detachably seatable 20 on and supported only by said mandrel, and a clamping device on said table for acting on said pour plate to clamp the work between the pour plate and work support and to adjust said mandrel downwardly to accommodate the size of the work.

25. In a bearing lining machine adapted to simultaneously cast bearing material onto all sections of a multi-section bearing ring without interfering with separation of the bearing sections 30 which comprises opposed members for receiving a multi-section bearing ring therebetween, means releasably acting on said members to clamp the bearing therebetween, one of said members having gate passages therein for feeding molten bearing metal into the bearing ring, a mandrel 35 slidable disposed in the bearing ring, said mandrel having a contour to shape the inner surface of the bearing metal, and ribs extending radially from the mandrel into close proximity with the bearing ring along the dividing lines between the sections thereof to separate the bearing metal into sections coextensive with the bearing sections.

40. A casting machine comprising a stationary work supporting die having a vertical aperture,

a mandrel slidable in the aperture of said die and projecting above said die, spring means supporting said mandrel, said mandrel having a shaping surface along its length, a pour plate removably mounted on and supported only by said mandrel, said pour plate and said die having opposed depressions to receive the ends of a workpiece disposed between the pour plate and the die and around the mandrel, and a clamping device operable on said pour plate to move it and the mandrel against the thrust of the spring means downwardly for clamping said workpiece against said die plate and to adjust the effective length of the shaping surface of said mandrel to the height of the workpiece.

7. A casting machine comprising a work-positioning die, a mandrel mounted for slidable vertical movement in said die and having groove-forming ridges on its surface, a spring-pressed support means for said mandrel, a bolt for limiting the upward movement of said mandrel, a pour plate detachably mounted on said mandrel, and clamping means for securing the work piece between said pour plate and said die.

8. A casting machine comprising a support 25 block having a bearing receiving surface with an aperture therein, a resiliently mounted mandrel slidable in the aperture and extending through the bearing to provide an elongated bearing form-

5
10

ing surface, a pour plate mounted on said mandrel having ports communicating with the interior of the bearing around the mandrel, and clamping means associated with said pour plate for clamping the bearing between the pour plate and said support block and for automatically adjusting the length of the bearing forming surface of the mandrel to the length of the face of the bearing.
